[57] CLAIM

The ornamental design for a collapsible fishing rod holder, as shown and described.

DESCRIPTION

FIG. 1 is a perspective view of our new collapsible fishing rod holder;

FIG. 2 is a top plan view of the same;

FIG. 3 is a bottom plan view of the same;

FIG. 4 is a right side elevational view of the same;

FIG. 5 is a left side elevational view of the same;

FIG. 6 is a front elevational view of the same; and

FIG. 7 is a rear elevational view of the same.

The fishing rod and reel shown in broken lines in FIG. 1 are disclosed for illustrative purposes only and form no part of the claimed design.
